UNITED STATES PATENT OFFICE.

JACOB K. GILCREST, OF DES MOINES, IOWA, ASSIGNOR TO THE DES MOINES INCUBATOR COMPANY, OF SAME PLACE.

DESIGN FOR A THERMOSTATIC CHAMBER.

SPECIFICATION forming part of Design No. 28,950, dated June 28, 1898.

Application filed February 17, 1898. Serial No. 670,711. Term of patent 7 years.

To all whom it may concern:

Be it known that I, JACOB K. GILCREST, a citizen of the United States of America, and a resident of Des Moines, in the county of Polk and State of Iowa, have invented a new and useful Design for a Thermostatic Chamber, of which the following is a specification.

The object of this invention is to produce a design for thermostatic chambers or cells to be employed in operating regulating mechanism.

My invention consists in the design herein-after set forth, pointed out in my claim, and illustrated by the accompanying drawings, in which—

Figure 1 is a perspective of the completed cell, illustrating my design therefor. Fig. 2 is a bottom plan of the completed cell. Fig. 3 is a cross-section of the cell on the indicated line 3 3 of Fig. 2.

According to my design the cell is of equilateral triangular form in plan view and elongated oval in elevation or cross-section and is hollow. The design is produced by and comprises upper and lower members 10 11, respectively, of the same shape—namely, that of the figure known as an "equilateral triangle." The members 10 11 are concavo-convex, and the concaved faces thereof approximate each other, the margins of the members 30 contacting.

I claim as my invention—

The design for a thermostatic chamber or cell, substantially as herein shown and described.

JACOB K. GILCREST.
